Primary Examiner — Mark Goodwin*(74) Attorney, Agent, or Firm* — Rebecca L. Henkel**CLAIM**

The ornamental design for a self-propelled sprayer, as shown and described.

DESCRIPTION

FIG. 1 is an isometric view of a self-propelled sprayer in accordance with the present invention;

FIG. 2 is a rear elevation view of the self-propelled sprayer of FIG. 1;

FIG. 3 is a side elevation view of a first side of the self-propelled sprayer of FIG. 1;

FIG. 4 is a top plan view of the self-propelled sprayer of FIG. 1;

FIG. 5 is a side elevation view of a second side of the self-propelled sprayer of FIG. 1; and,

FIG. 6 is a front elevation view of the self-propelled sprayer of FIG. 1.

The broken line showing of the sprayer vehicle is included for the purpose of illustrating environmental structure only and forms no part of the claimed design.
